United States Patent Office

Des. 229,567
Patented Dec. 11, 1973

229,567

RADIO PAGER OR SIMILAR ARTICLE

Arnold S. Goldman and Donald K. Krumin, Fort Lauderdale, Fla., assignors to Motorola, Inc., Franklin Park, Ill.

Filed Aug. 4, 1971, Ser. No. 169,157

Term of patent 14 years

Int. Cl. D14—03
U.S. Cl. D26—14 K

Fig. 1

Fig. 2

Fig. 3

Fig. 4

Fig. 5

FIG. 1 is a perspective view of a radio pager or similar article showing our new design;

FIG. 2 is a top plan view thereof;

FIG. 3 is an end elevation as seen from the right of FIG. 1;

FIG. 4 is an end elevation as seen from the left of FIG. 1;

FIG. 5 is a bottom plan view thereof.

The undisclosed side of the radio pager is identical to the side illustrated in FIG. 1.

We claim:

The ornamental design for a radio pager or similar article, substantially as shown and described.
